UNITED STATES PATENT OFFICE.

ROSARIO CELESTE, OF NEW YORK, N. Y.

DESIGN FOR A BASE FOR DISPLAY STANDS.

Application filed March 5, 1929. Serial No. 30,319. Term of patent 7 years.

To all whom it may concern:

Be it known that I, ROSARIO CELESTE, a citizen of France, residing at New York, in the county of New York and State of New York, have invented a new, original, and ornamental Design for a Base for Display Stands, of which the following is a specification, reference being had to the accompanying drawing, forming part thereof.

Fig. 1 is a plan view of a base for display stands, showing my new design.

Fig. 2 is a side elevational view of the same.

I claim:

The ornamental design for a base for display stands, as shown.

In testimony whereof I have affixed my signature.

ROSARIO CELESTE.
